UNITED STATES PATENT OFFICE.

LEOTUS E. HOLCOMB, OF LURAY, KANSAS.

PINLESS CLOTHESLINE.

Application filed February 7, 1928. Serial No. 252,659.

This invention relates to clotheslines, and the general object of the invention is to provide a clothesline which does not require the use of pins.

5 A further object is to provide a clothesline which is made up of a series of links, each link having a resilient clamping portion which is adapted to resiliently clamp upon a garment or other article and hold it in place 10 upon the clothesline.

My invention is illustrated in the accompanying drawing, wherein:—

Figure 1 is an elevation of a clothesline constructed in accordance with my invention;

Figure 2 is an elevation of one of the individual links.

Referring to this drawing, particularly to Figure 1, it will be seen that the clothesline 20 is composed of a series of interlinked elongated elements or units 10 each of said elements or units being formed of a length of resilient wire having a medial straight portion 11 and two terminal portions 15 resiliently bent to form relatively straight arms 12 and 14 extending across each other and beyond the opposite ends of said straight portions and through the bends or bights 15 and pressing against said bends or bights 15 to 30 form resilient clamps. The outer ends of each of the portions 12 and 14 terminate in eyes or heads 16.

Any number of these loops may be engaged with each other to form a flexible clothesline, 35 and the portions 12 and 14 are adapted to be sprung away from the loop for the insertion of an article between these portions 12 and 14 and the bights 15 so that the article is resiliently clamped between the resilient arms 12 and 14 and the bight portions of the loop. The article may be thus resiliently clamped at opposite ends of each link. The links are engaged with each other in the manner shown in Figure 1 so as to form a full sized 40 clothesline and such a clothesline will not require any clothes pins or other attaching devices.

The clothesline is strong, flexible, may be made of any desired length, and has been 45 found effective in actual practice. While I

do not wish to be limited to the particular detail now to be described, I preferably so form the extremities of the two arms 12 and 14 as to provide clamps. To this end, the extremities of these arms 12 and 14 are bent 55 around in a circle, as at 16, and the extremity of the wire bent inward diametrically at 17. The circle 16 at its intersection with the diametrical portion 17 is disposed outward of the adjacent portion of the arm 12 or 14 60 and bears against the same, thus providing a clamp within which clothes may be placed so that I thus provide for supporting clothes at a plurality of points upon the links.

The construction which I have provided is 65 very simple and effective. Clothes may be clamped between the arms 12 or 14 and the adjacent ends of the loop 11 by merely pulling the arms outward and inserting portion 70 of the clothes between these arms. Articles 75 may also be disposed between the loop 16 and the adjacent extremity of the arm 12 or 14 and thus a large number of garments may be readily supported upon the line, or where the garments are large they may be supported 80 by a large number of clamps.

I claim:—

1. A clothesline formed of a series of interlinked elongated elements, each of said elements formed of a length of resilient wire 80 having a medial straight portion and two terminal portions reversely bent and extending beyond the opposite ends of said straight portions and through the bends and pressing against said bent portions to form clamps. 85

2. A clothesline formed of a series of interlinked elongated elements, each of said elements formed of a length of resilient wire having a medial straight portion and two 90 reversely bent terminal portions, the ends of the wire extending beyond the opposite ends of said straight portion to form arms extending diagonally across each other and through said bends and pressing against the bent portions to form clamps, the extremity of said 95 arms terminating in approximately circular resilient clamping eyes.

In testimony whereof I hereunto affix my signature.

LEOTUS E. HOLCOMB.
